UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE CUFF-LINK.

1,317,267.

Specification of Letters Patent. Patented Sept. 30, 1919.

Application filed January 31, 1919. Serial No. 274,314.

To all whom it may concern:

Be it known that I, FRED S. CARR, a citizen of the United States, and a resident of Newton, in the county of Middlesex, Commonwealth of Massachusetts, (whose post-office address is care of Carr Fastener Company, Cambridge, Massachusetts,) have invented an Improvement in Separable Cuff-Links, of which the following description, 10 in connection with the accompanying drawings, is a specification, like characters on the drawings representing like parts.

This invention pertains to improvements in separable cuff links.

15 Referring to the drawings, which show a preferred form of one illustrative embodiment of my invention:

Figure 1 illustrates a preferred method of separating the two cuff-engaging portions of 20 one form of my invention by pulling outwardly on one side of the cuff at a point above the cuff link, thereby to tip the two portions of the link, one relative to the other, and effect separation thereof;

25 Fig. 2 is a cross-section of a preferred form of link taken on the line 2—2 of Fig. 1;

Fig. 3 is a section on the line 3—3 of Fig. 2;

30 Fig. 4 is an elevation, partly in section, taken on the line 4—4 of Fig. 2; and

Fig. 5 shows a modification of the separable button shown in the other figures, which modification is particularly well adapted for 35 use with stiff cuffs, the heads of the link being angled to conform to the flare of the ends of the cuff.

Great annoyance has heretofore been caused to users of separable cuff links arising from either of two causes;—if the separable portions of the cuff link were positively locked against accidental separation, the links have been difficult to join together and to separate, while separable cuff links 45 as heretofore constructed which have been easy to separate and snap together have proved unsatisfactory because likely to be accidentally separated. It is one of the objects of the present invention to provide a 50 cuff link which can be readily separated and joined together without complicated manipulation, but which is not subject to accidental separation.

In the preferred form of my invention, 55 the two portions of the stud are easily sepa-

ralable by relative tipping movement in at least one direction and are locked, preferably positively, against separation by relative tipping movement in at least one direction, viz., that direction in which the two 60 portions of the link are naturally tipped by the angling of the opposite ends of the cuff.

In the illustrative form of my invention shown in the drawings, I have shown coöperating stud and socket members, one carried by one end of the cuff and the other by the other end of the cuff, the stud and socket being formed to permit relative separation of stud and socket and of the opposite ends of the cuff by relative tipping movement in 70 two directions, viz., by tipping movement, as shown in Fig. 1, longitudinally of the cuff and exerted from above or by tipping movement in the opposite direction and longitudinally of the cuff which would be caused by 75 grasping one lower corner of the cuff and pulling it away from the adjacent corner thereof. It is not at all essential that separation be effected by tipping movement in more than one direction, but it is obviously 80 desirable to be able to effect separation by tipping movement in two directions in case the stud be placed in the socket in reversed relation, that is, in case that portion of the stud shown in Fig. 1 as adjacent the lower 85 edge of the cuff were to be positioned toward the upper edge of the cuff. If the button, or even one portion thereof, were always placed in the same relation to the cuff it would not be necessary to have the stud and socket lock 90 against separation by relative tipping movement in more than one direction, viz., that direction in which force is exerted by the angling of the cuff; but, in view of the fact that the shanks and heads of the button may 95 be made in various forms, some of which might be reversible, I prefer, as shown, that the stud and socket be locked against separation by relative tipping movement in both directions longitudinally of the cuff button-hole shown in Fig. 1.

As either the stud or the socket, or both, can or must determine the direction or directions in which separation can be effected by relative tipping movement and the direction or directions in which the parts are locked against separation by relative tipping movement, I preferably provide the direction-determining member or members with means coöperating with the shape of the 110

buttonhole in the cuff for predetermining and maintaining a given relative position or positions of the determining member or members to the cuff. It is, however, practicable 5 in some instances to determine the relation of the determining member or members to the cuff by the angling of the outside heads of the link relative to the flare of the cuff.

In the preferred form of my invention 10 shown in the drawings, the stud is symmetrical, having a head 5 and a neck portion 6 providing therebetween a relatively abrupt shoulder. The stud 5 may be, as shown, connected to a shank portion carrying 15 a shoulder 7 and an outside head 8, between which members 7 and 8 is held one end of the cuff 9. In that form of my invention selected for illustrative purposes the socket is the part which determines the 20 direction or directions in which separation of stud and socket may be effected by relative tipping movement. This socket may comprise, as shown in Fig. 2, a casing 10 carrying a spring 11 providing jaw portions 25 12 adapted to engage behind the head of the stud member and adapted to be wedged apart from beneath the shoulders of said stud member when the stud and socket are tipped one relative to the other in a direction 30 longitudinally of the jaws 12-12. In the preferred form of the invention shown in the drawings, relative tipping movement of stud and socket in a direction transversely of the jaws 12-12 is prevented, not 35 only by the engagement of the jaws with the shoulder behind the head of the stud, but also by the shape of the opening in the face of the socket, which opening is elongated as best shown in Fig. 4. The buttonholes in 40 cuffs almost invariably extend in a direction circumferentially thereof, or, in other words, transversely thereof. In that form of my invention shown in the drawings I have taken advantage of this to provide a 45 shank portion on the direction determining member, viz., in this instance the socket, which shank portion is elongated in a direction transversely of the jaws 12-12, thereby 50 insuring the positioning of the stud in the cuff in such a way that separation by relative tipping movement of the parts can only be effected in a direction longitudinally of the cuff, viz., in a direction transversely of the buttonhole as shown in Fig. 1. Where 55 the head of the cuff link is angled to conform to the flare of the stiff cuff, as shown in Fig. 5, the angle of the head of the stud may be used as the determining factor instead of the elongated shank portion as 60 shown in Fig. 2.

In use, the two portions of the separable stud may be inserted in their respective cuff buttonholes, after which the head of the stud should be entered in the aperture opposite 65 the opening in the socket and, when the two

outside heads of the link are pressed toward each other, the rounded head of the stud will spring apart the two jaws 12-12, thereby permitting the stud to enter the socket until the jaws 12-12 snap into the neck of the stud. The cuff link is now locked against separation by relative tipping movement in the direction of the angling of the stud and, in the preferred form of my invention shown in the drawings, it is locked against separation by tipping movement in the diametrically opposite direction also. The two parts of the cuff link may, however, be readily separated by tipping movement in a direction longitudinally of the cuff, viz., in a direction transversely of the cuff button-hole shown in Fig. 1. This can very readily be effected by inserting the finger of the other hand in the opening above the cuff link and exerting a slight force or pull thereon in a direction toward the observer in Fig. 1, in other words, away from that end of the cuff which has not been engaged by the finger. In the preferred form of my invention selected for illustrative purposes, separation can also be effected by taking hold of one lower corner of the cuff and giving it a pull away from the adjacent corner of the cuff. It is, however, obvious that anywhere from one to three directions in which separation may be effected by tipping movement may be provided without departing from the scope of my invention, and that anywhere from one to three directions in which the locking of the parts against separation by tipping movement is provided may also be supplied without departing from the scope of my invention. In fact, while I have shown and described a preferred form of one embodiment of my invention, it will be understood that changes involving omission, substitution, alteration and reversal of parts, and even changes in the mode of operation, may be made without departing from the scope of my invention, which is best defined in the following claims.

Claims:

1. A separable cuff link including coöperating stud and socket members locked against separation by relative tipping movement in one direction, and formed to permit separation by relative tipping movement in another direction.
2. A separable cuff link including coöperating stud and socket members locked against separation by relative tipping movement in two directions and formed to permit separation by relative tipping movement in two other directions.
3. A separable cuff link including coöperating stud and socket members locked against separation by relative tipping movement in one direction, formed to permit separation by relative tipping movement in another direction, and positioning means op-

posing rotation of at least one of said members relative to the coöperating cuff button-hole.

4. A separable cuff link including coöperating stud and socket members separable by relative tipping movement in at least one direction and locked against separation by relative tipping movement in at least one direction, and means for determining and 10 maintaining a predetermined relationship between the cuff and at least one of said members.

5. A separable link including coöperating stud and socket members located between the 15 cuffs, said members locked against separa-

tion by tipping movement in the direction of angularity of the opposite edges of the cuff, but separable by relative tipping movement in another direction.

6. A separable cuff link including coöperating stud and socket members located between the cuffs, said members locked against separation by tipping movement in the direction of angularity of the opposite edges of the cuff, but separable by relative tipping 20 movement longitudinally of the cuff in another direction.

In testimony whereof, I have signed my name to this specification.

FRED S. CARR.
